UNITED STATES PATENT OFFICE

2,599,117

LADDER EXTENSION

Joe E. Maxson, Sandusky, Ohio

Application October 13, 1949, Serial No. 121,132

1 Claim. (Cl. 228—63)

1

This invention relates to a ladder rail extension attachment, whereby a ladder may be used upon an uneven surface.

A primary object of the present invention is to enable a ladder to be used upon both flat surfaces and surfaces of various degrees of unevenness.

Another important object of this invention is to enable an operator to efficaciously adjust a conventional ladder in conformity with the characteristics of the supporting surface.

A meritorious feature of the present invention resides in the simplicity of construction, and the ease with which it is mounted upon conventional ladders.

Still another important feature of the present invention resides in its light weight and its compactness which does not substantially increase the dimensions or weight of a ladder.

A final important feature to be specifically enumerated herein resides in the use of spaced C-shaped guides and the integral construction of the extension element.

These, together with various ancillary features and objects of the invention which will later become apparent as the following description proceeds, are attained by the present invention, a preferred embodiment of which has been illustrated by way of example only in the accompanying drawings, wherein:

Figure 1 is a front elevational view of the present invention, showing the same attached to a conventional ladder and in use upon an uneven supporting surface;

Figure 2 is a side elevational view of the present invention, showing the same attached to a conventional ladder rail; the attachment being shown extended from the ladder rail;

Figure 3 is a side elevational view of the present invention, showing the same attached to a conventional ladder rail and in the retracted position;

Figure 4 is a horizontal transverse sectional view taken upon the plane of the section line 4—4 of Figure 1;

Figure 5 is a vertical sectional view, being taken substantially upon the plane of the section line 5—5 of Figure 2; and,

Figure 6 is a perspective view of the extension element and the attached guide plates of the present invention.

Reference is now made more specifically to the accompanying drawings, wherein like numerals designate similar parts throughout the various views, and in which the numeral 10 designates a conventional ladder having rails 12.

The subject matter of the present invention comprises a channel member 14 having marginal offset flanges 16, the channel member being suitably secured to the rail 12 as by fasteners 18 ex-

5 tending through the channel member 14 as shown in Figure 5. A pair of C-shaped plates 20 and 22 slidably engage the channel member with the extremities of the plates 20 and 22 preferably engaging both the flanges 16 and the lateral extremities of the channel member 14 as shown in Figure 4.

10 Plates 20 and 22 are suitably secured to an extension element 24 in spaced relation as by welding 26. The element 24 is formed of an integral U-shaped rod formed to provide legs 28 and having a bight portion 30, the legs 28 being bent adjacent the bight portion 30 to constitute a foot 32 for the extension element 24. In the preferred construction a lower end of the rail 12 is provided 15 with grooves 34 to receive the foot 32 upon the retraction of the element 24 on the rail 12, it being obvious that this arrangement permits the ladder 10 to be used upon an even surface without interference from the present invention.

20 The plate 20 is provided with an aperture 36 and a pair of ears 38. A pawl 40 having a dog 42 is pivoted to the ears 38 as at 44, with the dog 42 extending through the aperture 36 to engage 25 ratchet teeth 46 on the channel member 14. A spring 48 is secured to the plate 20 for urging the dog 42 into engagement with the teeth 46. As best shown in Figure 5, the dimensions of the aperture 36 are such that the pawl 40 will prevent upward movements of the element 24 relative 30 to the rails 12, that will permit the pawl 40 to ratchet on the teeth 46 when extending the element 24.

25 The present invention has several conspicuous advantages in that the extension 24 may be retracted readily to a non-operative position, or may alternatively be readily slipped entirely from engagement with the channel member and the rail 12. It is to be noted that the present invention does not substantially increase the overall 40 dimensions of the ladder after being applied thereto, nor does the present invention add appreciably to the weight of the ladder. The weight reduction accomplished by the construction of the element 24 and of the plates 20 and 22 is an 45 important factor when it is considered that a ladder to which any such extension arrangement is applied must be carried from place to place by workmen.

50 The spacing of the legs 28 exposes the ratchet teeth 46 to view whereby the condition of the same and the tightness of the fasteners 18 may be readily ascertained, as well as enabling an operator to readily lubricate the teeth 46 if desired. It will be noted that the element 24 as well as the latching means and the plate 20 and 55 22 may be removed from the channel member as a unit when the use of the same is not contemplated on a particular job.

60 It is contemplated that the present invention

will be found very useful when attached to a conventional ladder for use on the uneven ground of orchards, stair steps or the like, and that the particular configuration of the foot 32 will provide the maximum assurance against slipping of the same.

From the foregoing, the construction and operation of the device will be readily understood and further explanation is believed to be unnecessary. However, since numerous modifications and changes will readily occur to those skilled in the art after a consideration of the foregoing specification and accompanying drawings, it is not desired to limit the invention to the exact construction shown and described but all suitable modifications and equivalents may be resorted to falling within the scope of the appended claim.

Having described the invention, what is claimed as new is:

For use with a ladder rail, an extension attachment comprising an elongated channel member having marginal offset flanges, said channel member being mountable on a ladder rail with

said flanges spaced from said rails, a pair of C-shaped plate members slidably engaging said flanges, an extension element comprising an integral U-shaped rod having a bight portion and a pair of legs, each of said plate members being secured to and spaced apart by said pair of legs, said pair of legs having portions bent adjacent said bight portion to define a foot for said extension element, ratchet teeth on said channel member, and a pawl carried by said extension element and engaging said ratchet teeth.
